GAUGE LOCK FOR A RULE

Raymond P. Ricker, 20 Bartlett Ave.,
Somersworth, N.H. 03878

Filed Nov. 21, 1969, Ser. No. 20,210

Term of patent 14 years

Int. Cl. D10—08

U.S. CL. D52—6

FIG1

FIG2

FIG3

FIG4

FIG. 1 is a perspective view of a gauge lock for a rule showing my new design;

FIG. 2 is a left end elevational view;

FIG. 3 is a front elevational view; and

FIG. 4 is a top plan view.

I claim:

The ornamental design for a gauge lock for a rule, substantially as shown.
